UNITED STATES PATENT OFFICE.

PETER SIVERTSEN, OF NEW YORK, N. Y.

ABRADING DEVICE.

Application filed November 24, 1925. Serial No. 71,062.

This invention relates to sharpening devices and has more special reference to knife sharpeners adapted for use on slicing machines.

5 While the present invention is more especially adapted for use with the slicing machine disclosed in my copending application S. N. 319,059, filed August 22nd, 1919 in which a horizontal bar is located near the 10 rotary knife nevertheless the present invention may also be applied to other types of machines in which a supporting bar is found available and also to appliances other than slicing machines.

15 Comprehensively stated the present invention comprises an abrading element which is so mounted as to be capable of a universal compensatory movement so that the knife may be ground at any bevel.

20 While one embodiment of the present invention is disclosed in the accompanying drawing, it is to be understood that this embodiment merely serves as an illustration of the underlying principles of the invention so 25 that they may be readily comprehended by those skilled in the art and are not intended as limiting the invention to the specific form disclosed therein.

In said drawing:—

30 Fig. 1 is a top plan view of the invention.
Fig. 2 is a section of Fig. 1 on the line

2—2.

Fig. 3 is an end elevation of the invention and

35 Fig. 4 is a section of Fig. 1 on the line
4—4.

40 Continuing now by way of a more detailed description, a driven rotary knife which is to be sharpened is indicated by A and a suitable rest or supporting bar is indicated by B. While the bar B is shown as an appurtenant to a slicing machine it is to be understood that the bar B might also be any bar which is temporarily placed in 45 position to afford a support for the device.

45 Irrespective of whether the bar is a permanent appurtenant to a slicing machine or other apparatus or is merely a temporary expedient, as above indicated, a rockable yoke C

having oppositely disposed dependent forked flanges C' is adapted to be set on the bar B with the forked ends C' straddling it. This yoke has an aperture or bearing at D for receiving a longitudinally slideable manipulating bar or handle E adapted to be moved 50 either toward or away from the knife A and to rotate about its longitudinal axis to change the plane of the abrading element F, which may be and preferably is an emery wheel mounted at one end of the bar E in 55 a manner to be more fully described hereinafter. The adjustment toward or away from the knife affords means for accommodating the grinder to the knife's wear while the change in inclination of the plane of the 60 abrading element affords means to control the bevel and also to present fresh surfaces of the abrading element to the knife edge. A set screw G of any convenient type is arranged to lock the bar E in predetermined 65 position for grinding the knife and the pressure of the wheel F against the knife is accomplished by bearing down on the handle in the direction of arrow "X" and tilting the yoke C about the bar B as a fulcrum. The 70 dependent flanges C' "hook over" the bar and afford a firm support for the yoke and yet permit the device to be quickly and easily applied and removed from the bar.

75 The abrading element F consists of an 80 abrading disk of a suitable abrading material for example emery which is carried on a rotatable spindle F' which in turn is journaled in a detachable socket H, the socket having its upper end flanged at H' to prevent it from passing through its receiving aperture in the end of the arm E when pressure is applied to the arm E in the direction indicated. The lower portion of the journal bearing has a suitable thrust member H'' to 85 afford a bearing on which the lower end of the spindle may turn.

90 It is claimed:

1. An abrading device for slicing machines combining a manually operable bar, a 95 rotatable abrading element mounted on said bar, a stationary bar, a support having oppositely disposed dependent flanges adapted to

straddle the stationary bar, and an opening in the support adapted to receive the manually operable bar.

2. An abrading device for slicing machines combining, a stationary bar, a yoke having oppositely disposed dependent flanges each of which is forked and adapted to straddle the bar, an arm slidably and ro-

tatably mounted in said support, a detachable flanged socket in said arm, a rotatable 10 abrading disk, a spindle carrying said disk and journalled in the socket.

Signed at the city of New York in the county of New York, and State of New York, this 6th day of May, 1924.

PETER SIVERTSEN.
